UNITED STATES PATENT OFFICE.

LEWIS R. McLAIN AND ROY H. McLAIN, OF CLEVELAND, OHIO.

JOURNAL-BOX.

SPECIFICATION forming part of Letters Patent No. 761,246, dated May 31, 1904.

Application filed January 2, 1904. Serial No. 187,481. (No model.)

To all whom it may concern:

Be it known that we, LEWIS R. McLAIN and Roy H. McLAIN, citizens of the United States, residing at Cleveland, in the county of Cuyahoga and State of Ohio, have invented new and useful Improvements in Journal-Boxes, of which the following is a specification.

This invention relates particularly to car-
axle journal-boxes; and its object is to pro-
vide an improved fluid-pressure-controlled
lock for preventing the theft or unauthorized
removal of the brasses or bearings from the
box.

A further object is to provide improved
means for supporting the brass in the box
both when the journal is in the box and when
it is removed therefrom.

In the accompanying drawings, Figure 1 is
an end view of a car journal-box with the lid
removed. Fig. 2 is a top view thereof. Fig.
3 is a vertical section on the line 3-3 of Fig.
2, and Fig. 4 is a perspective view of the cyl-
inder containing the pressure-actuated piston
which controls the lock.

Referring specifically to the drawings, 6 in-
dicates a car journal-box of ordinary construc-
tion; 7, the car axle or journal therein; 8, the
bearing-brass, and 9 the key which holds the
latter in place. In the side wall of the box
30 opposite the edge of the brass a hollow cas-
ing 10 is cast. This casing opens into the in-
side of the box through the side wall thereof
and has through the top a small hole 11 for
the air-pipe nipple, but is otherwise closed
35 throughout, so that the lock cannot be tam-
pered with either with or without tools.
Within said casing is inserted a cylinder 12,
closed at the inner end, except a small vent
at 13, and closed at the outer end by remov-
40 able cap 14. This cylinder contains a piston
15, behind which is a coiled spring 16. The
piston has a stem or bolt 17, which extends
through a hole in the cap 14 and projects
within the journal-box, where it enters a hole
45 8^a, produced in the side edge of the brass.
Opening into the cylinder on the side of the
piston opposite the spring is a nipple 18,
which projects through the hole 11 hereto-
fore referred to. This nipple is adapted to
50 receive a coupling of a pipe from the air-

brake system or from any convenient air-
pump to release the lock.

In use the pressure of the spring 16 forces
the piston toward the end of the casing near-
est the journal-box, with the bolt or stem 17 55
in the hole in the edge of the brass, whereby
the brass is locked against removal. To re-
lease the lock, air or other fluid pressure is
forced in through the nipple until the pres-
sure of the spring is exceeded, when the pis- 60
ton will move back and withdraw the stem
from the hole in the brass, which can then be
removed in the usual manner.

In case the axle has to be taken out of the
box for any reason the stem in the hole in the 65
brass acts to support the latter and to hold it
in position. Also it holds the brass in place
while the car is in motion and prevents any
accidental displacement of the brass.

The embodiment illustrated shows only one 70
cylinder; but it is within the scope of our in-
vention to duplicate the same on the other side
of the box, thereby affording double security
against theft and also holding the brass in
place better. 75

What we claim as new, and desire to secure
by Letters Patent, is—

1. The combination with a journal-box, and
brass therein, of a locking-bolt engaging the
brass and inaccessible without removing the 80
brass, and means to operate said bolt and to
lock the same against unauthorized operation
thereof.

2. The combination with a journal-box and
brass, of a concealed and exteriorly-inaccessi- 85
ble locking device carried by the box and engag-
ing and supporting the brass and con-
structed to prevent unauthorized unlocking.

3. The combination with a journal-box, and
a brass therein, of a locking-bolt engaging 90
the brass, and fluid-operated means to unlock
and operate said bolt.

4. The combination with a journal-box and
brass, of a spring-pressed bolt supported on
the box and engaging the brass, and means 95
to disengage the bolt from the brass.

5. The combination with a journal-box and
brass, of a spring-pressed bolt supported on
the box and engaging the brass, and means op-
erated by fluid-pressure to disengage the bolt. 100

6. The combination with a journal-box, and a brass therein having a hole in the edge, of a locking-bolt concealed and inclosed in a casing and working through the wall of the box and into said hole, and means to unlock and operate said bolt.

7. The combination with a journal-box having a brass therein, of a cylinder on the box, a piston slideable in said cylinder, a bolt projecting from the piston into engagement with the brass, a spring in the cylinder on one side of the piston, and a fluid-pressure inlet to the cylinder on the other side of the piston.

8. The combination of a journal-box having a casing thereon opening into the box, a cyl-

inder in the casing, a spring-pressed piston in the cylinder, having a stem projecting into the box, a brass in the box having a hole into which the stem fits, and a fluid-pressure inlet through the casing and into the cylinder on the side of the piston opposite to the spring. 20

In testimony whereof we have signed our names to this specification in the presence of two subscribing witnesses.

LEWIS R. McLAIN.
ROY H. McLAIN.
